UNITED STATES PATENT OFFICE

2,037,549

IRONING MACHINE

John S. Visscher, Bridgeport, Conn., assignor to
General Electric Company, a corporation of
New York

Application September 25, 1934, Serial No. 745,428

19 Claims.

(Cl. 68—9)

My invention relates to ironing machines of the type in which ironing is effected by the pressure between a heated shoe and a buck.

The object of my invention is to provide an improved construction and arrangement in ironing machines of this type, and for a consideration of what I believe to be novel and my invention, attention is directed to the accompanying specification and the claims appended thereto.

In the accompanying drawing, Fig. 1 is a sectional end elevation of an ironing machine embodying my invention; Fig. 2 is a fragmentary plan view partly broken away of the front end of the carriage; Fig. 3 is a sectional view taken on line 3—3 of Fig. 2; Fig. 4 is an exploded view of part of the mechanism for moving the shoe into final pressing engagement with the buck; Fig. 5 is an end elevation of the drain pan and the support therefor, and Fig. 6 is an enlarged fragmentary view of the pressure mechanism as shown in Fig. 1.

The ironing machine is carried on a hollow base 1. The front end of the upper wall of the base is provided with a depression 2 which provides a tray for pins and the like. The rear upper wall of the base is turned up at 3 to provide an apron which will prevent the surplus of the material being ironed from falling over the rear edge of the base. The upper side of the base is provided with a rectangular depression 4 in which is placed the lower edge of a hollow member 5 made of rubber or other resilient material for supporting a hollow buck 6. The upper edge of the member 5 fits within the depending sides of a rectangular cup 7 which is attached to the lower side of the buck at the center. The rectangular shape of the member 5 prevents turning of the buck. A bolt 8 having a head fitting within a tapered opening 8a in the lower wall of the buck extends through an opening 9 in the upper wall of the base, secures the buck to the base, and holds the upper and lower ends of the member 5 in firm contact with the rectangular cup 7 and the depression 4. The opening 9 is larger than the bolt and allows some lateral movement of the bolt. A rubber washer 10 placed between a nut 11 on the bolt and the upper side of the base resiliently holds the bolt in position in the opening 9. With this arrangement the buck is resiliently supported so that it can tilt in all directions in order to maintain an even pressure over the surface of the buck during ironing.

The buck 6 is hollow and is fabricated from a metal shell 12 having sides which flare outwardly and upwardly from the cup 7 to provide the bot-

tom wall of the buck and are turned up at 12a to provide the edges of the buck. The front and rear sides and edges of the shell are connected by spaced transverse vertical ribs 13 having integral ears 13a spot welded to the shell at the edges and the bottom. A wire mesh screen 14 is placed across the upper edge of the ribs 13 and provides a support for a pad 15 and a pad cover 15a of textile material. The pad is held in place over the upper surface of the buck by cords 16 which are connected to the pad cover and are laced across the under side of the buck. The steam which is generated during ironing passes through the pad and the wire mesh into the interior of the metal shell 12, and when condensed flows along the bottom of the buck beneath the ribs 13 and is led through openings 16a in the bottom wall of the buck to the interior of the hollow member 5. From there, the condensed moisture is led through the upper wall of the base by a drain tube 17 to an opening 18a in a pan 18 carried on the under side of the base. The pan 18 is tubular and closed on all sides except for the opening 18a. The pan is supported by lugs 18b secured to the ends of the pan which rest in recesses in brackets 18c extending from the side wall of the base. A spring clip 18d carried by the side wall of the base presses down on the top of the pan so that the lugs 18b are held firmly in contact with the brackets 18c. The pan may be removed by lifting the rear end of the pan until the lug 18b is clear of the recess in the bracket 18c and sliding the pan to one side until clear of the spring clip 18d. The location of the hole in the pan is such that the condensed moisture will not be spilled if the machine is tipped when moving from one location to another. By withdrawing the steam generated during ironing, the pad is kept dry and the ironing speed is increased. The wire mesh 14 and the ribs 13 provide a construction which adequately supports the pad 15 and provides a large area for the steam to pass through the pad into the interior of the buck. The rubber member 5 and the rubber washer 10 provide seals which prevent the leakage of the condensed moisture over the outside of the base and into the interior of the base.

The carriage for supporting the shoe comprises a channel 19 of U-shaped configuration having a reinforcing web 19a secured between the flanges. 50 The lower arm 20 of the carriage is pivotally carried on the base between guides 20a by a pin 21 which fits within an elongated slot 22 formed in each flange of the channel. The slots 22 are inclined toward the lower arm 20.

that the pin 21 tends to remain at the front end of the slots 22 when the carriage is pivoted forward from the position shown in dotted lines in Fig. 1 to the position shown in full lines in Fig. 1. 5 A notch 23 is formed in the front end of the lower arm 20. The upper side 23a of the notch 23 projects beyond the lower side 23b of the notch so that when the carriage is pivoted forward, the lower side 23b swings past a pin 24 10 in the base and the upper side 23a engages the pin 24, stopping the pivotal movement of the carriage. From this position, the carriage is moved to the position shown in full lines in Fig. 1 by sliding the carriage forward on the pin 21 so 15 that the notch 23 engages the pin 24 and locks the carriage in this position. When the carriage is in this position, it cannot be displaced by forces perpendicular to the face of the buck on the upper arm of the carriage. To move the 20 carriage from the position shown in full lines to the position shown in dotted lines, the carriage is first pushed rearwardly so that the notch 23 is moved clear of the pin 24 and the pin 21 is at the front of slot 22. The carriage is then 25 pivoted rearward on the pin 21.

The buck is mounted so that the upper surface of the buck is inclined upwardly from the front. The inclined surface of the buck makes the adjustment of the clothes over the surface of the 30 buck easier. The travel of the pivoted carriage necessary to move the shoe out of register with the buck is decreased, and the tendency of the shoe to throw heat into the operated surface when in the out-of-register position is also decreased. 35

The inclined buck and its construction and the carriage which has been described above form no part of my invention, but are the invention of G. W. Wardwell and are claimed in application, 40 Serial No. 744,793, filed September 20, 1934.

A shoe 25 which is preferably made of aluminum or other suitable metal is supported on the lower side of the upper arm 26 of the carriage by two pins 21. The lower ends of these pins are threaded into the upper surface of the shoe at points intermediate the ends of the shoe on either side of the center of the shoe. The body of each of the pins passes through a bushing 28 which is secured at the lower end to a cross member 29 connected between the flanges of the upper arm of the carriage. A coil spring 30, surrounding the bushing and the pin and arranged between the cross member 29 and a washer 31 secured to the upper end of the pin, biases 50 the shoe upwardly against the lower side of the arm 26 of the carriage. The springs 30 permit the shoe to be moved away from the carriage, and the bushings 28 guide the movement of the shoe and permit a limited tilting of the shoe. 55

The shoe is heated by a heating element 32 which is clamped in a groove formed in the upper surface of the shoe by clamps 33. A switch 32a controls the flow of current to the heating element. A cover 34 is provided to enclose the upper surface of the shoe. 60

When the carriage is in the position shown in full lines in Fig. 1, the carriage is held against vertical movement by the pins 21 and 24, and the shoe 25 is in register with and in spaced relation to the buck. To move the shoe into pressing engagement with the buck, I have provided a low-pressure mechanism which moves the shoe relative to the carriage into engagement 70 with the buck and a heavy-pressure mechanism 75

which subsequently moves the shoe into final pressing engagement with the buck.

The low pressure mechanism has a hollow shaft 35 which is pivotally carried on the carriage by a bushing 36 secured to the under side 5 of the web of the upper arm 26 of the carriage. Pins 37 are secured at one end to the shaft and the projecting ends of the pins 37 fit within rounded recesses 38 in a sliding block or support 39. The recesses 38 prevent endwise displacement of the shaft 35. The block 39 slides in a guide 40 secured between the flanges of the upper arm of the carriage, and an ear 40a on the upper edge of the guide 40 limits the upward movement of the block. An operating lever 41 is connected to the projecting end of the shaft 35 for rotating the shaft. Rotation of the lever 41 in a counterclockwise direction, as viewed in Fig. 1, causes the pins 37 to force the block 39 downwardly against a plate 57 secured to the upper 20 surface of the shoe to force the shoe away from the carriage and into engagement with the buck. The leverage exerted by the lever 41 is such that only a low pressure is required to move the shoe against the action of springs 30 so that the shoe 25 is moved quickly and easily into contact with the buck. A stop 39a secured to the upper end of the block 39 engages the upper arm of the carriage and limits the movement of the block. The position to which the shoe and block 39 are moved 30 by the lever 41 depends on the thickness of the material placed on the buck, so that the low pressure mechanism adjusts for variation in thickness of the material being ironed. When the lever 41 is released, the springs 30 return the 35 shoe, the block, and the operating lever 41 to the position shown in full lines in Fig. 1.

The shoe is moved into final pressing engagement with the buck by a heavy-pressure mechanism which has a shaft 42 journalled in bushings 43 in the block 39. A cam 44 secured to the shaft 42 by a pin 46 fits within a recess 45 formed in the block 39 between the bushings 43. The bushings are lubricated by wicks 43a. A slot 45a is formed in the bottom and rear side wall of 45 the block through which the cam projects. The edges of the slot 45a prevent longitudinal displacement of the cam and the shaft 42. The working surface of the cam is provided with a roll 47 which is journalled between flanges 48 50 of the cam. The roll 47 engages the plate 57 secured to the upper surface of the shoe. When the block 39 is in the position illustrated in Fig. 1, it is free to slide up and down in the guide 40 relative to the upper arm of the carriage. In 55 order to lock the block 39 to the upper arm of the carriage so that the cam 44 may exert a pressure tending to move the shoe away from the carriage, I have provided a U-shaped pawl 49 which is carried within the recess 45 in the 60 block 39. The front and rear sides of the pawl are on each side of the shaft 42 and pivots thereon, and the bottom of the pawl rests on ledges 45b at the bottom of the block 39. A slot 49a is formed in the bottom of the pawl within which 65 the cam 44 may rotate without disturbing the pawl. The pawl has a pointed upper front edge 50 which is adapted to engage notches 51 in a plate 52 secured to the front wall of the guide 40 under the ear 40a. When the pawl engages 70 the notches 51, the bottom of the pawl which rests on the ledges 45b prevents upward movement of the block 39 and locks the block to the carriage. A spring 53 arranged in a recess 53a in the front of the block 39, urges the front edge 75

of the pawl toward the notches 51 in plate 52. A shoulder 54 formed on the cam engages the rear edge 55 of the pawl when the parts are in the position shown in Fig. 1 and holds the pawl out of engagement with the notches 51 against the force of spring 53. The force exerted by the springs 30 tend to maintain the cam 44 in the position to hold the pawl out of engagement with the notches 51. An operating lever 56 is connected to the projecting end of the shaft 42 for rotating the cam. The operating levers 41 and 56 are arranged on opposite sides of the upper arm of the carriage so that both levers cannot be operated with one hand. This increases the safety of the machine. A cover 58 secured to the upper arm of the carriage encloses the pressure-developing mechanism.

When the lever 56 is moved in a counterclockwise direction, as viewed in Fig. 1, the initial movement of the handle moves the shoulder 54 on the cam away from the rear edge 55 of the pawl and allows the spring 53 to move the edge 50 of the pawl into engagement with the notches in the plate 52. The friction of the shaft 42 on the pawl assists spring 53 in moving the pawl into engagement with the notches. This locks the block 39 in the position to which it has been moved by the lever 41. Continued rotation of the lever 56 in a counterclockwise direction causes the roller 47 of the cam 44 to move the shoe relative to the carriage into final pressing engagement with the buck. The roller 47 is moved past the center line of the shaft 42 so that the cam will remain in this position. The rear edge 44a of the cam engages the block 39 above the slot 45a and limits the rotation of the cam. Since the low pressure mechanism moves the shoe into contact with the buck and moves the block 39 to a corresponding position, the cam of the heavy-pressure mechanism needs only a small throw, so that the force of reaction of the lever 56 when released by the operator is small. The block 39 is locked to the carriage by the pawl 49 until the operating lever 56 is returned to the position shown in Fig. 1, at which position the shoulder 54 engages the rear edge of the pawl and moves the front edge of the pawl out of engagement with the notches in the plate 52.

In the operation of the ironing machine, assume that the carriage is in the position shown in dotted lines in Fig. 1. In this position the shoe is out of register with the buck so that the operator may arrange the material to be ironed on the upper surface of the buck. To iron the material placed on the buck, the operator pivots the carriage about pin 21 by pulling on lever 41 and as the carriage approaches the position shown in full lines in Fig. 1, the lower edge 23b of the lower arm of the carriage swings past pin 24 and the upper edge 23a of the lower arm engages the pin 24, thus stopping further turning movement of the carriage. The operator then pulls on lever 41 to slide the carriage forward to bring the notch 23 over the pin 24, the elongated slots 22 permitting the carriage to be pulled forwardly on the pin 21. This locks the carriage in the position shown in Fig. 1. The operator now rotates the lever 41 in a counterclockwise direction, as viewed in Fig. 1, to cause the pins 31 to force the block 39 downwardly against the plate 57 on the upper surface of the shoe and move the shoe into contact with the material placed on the buck. The movement of the shoe and the block depends on the thickness of the material on the buck. To complete the ironing

operation, the operator rotates the lever 56 in a counterclockwise direction, as viewed in Fig. 1, while still holding lever 41 in the lowered position. The initial movement of the lever 56 moves the shoulder 54 on the cam away from the rear edge 55 of the pawl and permits the spring 53 to move the front edge 50 of the pawl into engagement with the notches 51 in the plate 52. This locks the block 39 to the carriage in the position to which it was moved by the lever 41. Continued rotation of the lever 56 causes the roller 47 of the cam to force the shoe into final pressing engagement with the buck. In this position, levers 41 and 56 may be released if desired. Since both hands are required to operate the machine, the safety of the machine is increased. To release the shoe, the operator first returns the lever 56 to the position shown in Fig. 1. The final return movement of the lever 56 causes the shoulder 54 of the cam to engage the rear edge 55 of the pawl to force the pawl out of engagement with the notches of the plate 52. The operator holds lever 41 until lever 56 is returned to the released position and then lets lever 41 return slowly under the action of the springs 30. This prevents sudden returns of the shoe and the lever 41. To uncover the surface of the buck so that the ironed material may be removed, the operator pushes on the lever 41. The initial effect of pushing on the lever 41 is to slide the carriage rearwardly so that the notch 23 is clear of the pin 24 and the pin 21 is in the front part of the slots 22. Continued rearward pressure on the lever 41 causes the carriage to pivot about the pin 21 and to return to the position shown in dotted lines in Fig. 1.

What I claim as new and desire to secure by Letters Patent of the United States is:

1. An ironing press comprising a buck, a carriage, a shoe carried by said carriage and movable relative to said carriage, means for relatively moving said buck and shoe to a position in which said buck and shoe are in register in spaced relation, low-pressure means for initially moving said shoe away from said carriage and toward said buck, and heavy-pressure means for subsequently moving said shoe relative to said carriage into final pressing engagement with said buck.

2. An ironing press comprising a buck, a carriage, a shoe carried by said carriage and movable relative to said carriage, means for relatively moving said buck and shoe to a position in which said buck and shoe are in register and in spaced relation, low-pressure means for initially moving said shoe away from said carriage and toward said buck, and heavy-pressure means moved with said shoe during the initial movement of said shoe for moving said shoe relative to said carriage into final pressing engagement with said buck.

3. An ironing press comprising a buck, a carriage, a shoe carried by said carriage and movable relative to said carriage, means for relatively moving said buck and shoe to a position in which said buck and shoe are in register and in spaced relation, low-pressure means for initially moving said shoe away from said carriage and toward said buck, heavy-pressure means moved with said shoe during the initial movement of said shoe for moving said shoe relative to said carriage into final pressing engagement with said buck, and means for locking said heavy-pressure means to said carriage in the position

to which it is moved during the initial movement of said shoe.

4. An ironing press comprising a buck, a carriage, a shoe carried by said carriage and movable relative to said carriage, means for relatively moving said buck and shoe to a position in which said buck and shoe are in register and in spaced relation, low-pressure means for initially moving said shoe away from said carriage 10 and toward said buck, heavy-pressure means moved with said shoe during the initial movement of said shoe for moving said shoe relative to said carriage into final pressing engagement with said buck, and means actuated by the initial movement of said heavy-pressure means for locking said heavy-pressure means to said carriage.

5. An ironing press comprising a buck, a carriage, a shoe carried by said carriage and movable relative to said carriage, means for relatively moving said buck and shoe to a position in which said buck and shoe are in register and in spaced relation, low-pressure means for initially moving said shoe away from said carriage 20 and toward said buck, heavy-pressure means moved with said shoe during the initial movement of said shoe for moving said shoe relative to said carriage into final pressing engagement with said buck, means for locking said heavy-pressure means to said carriage in the position to which it is moved during the initial movement of said shoe, and means actuated by movement of said heavy-pressure means in the direction to release the pressure between said buck and said 30 shoe for releasing said heavy pressure means from said carriage.

6. An ironing press comprising a buck, a carriage, a shoe carried by said carriage and movable relative to said carriage, means for biasing said shoe toward said carriage, means for relatively moving said buck and shoe to a position in which said buck and shoe are in register and in spaced relation, means for initially moving said shoe toward said buck in opposition to said biasing force, and means moved with said shoe during the initial movement of said shoe for moving said shoe relative to said carriage into final pressing engagement with said buck.

50 7. An ironing press comprising a buck, a carriage, a shoe carried by said carriage and movable relative to said carriage, means for biasing said shoe toward said carriage, means for relatively moving said buck and shoe to a position in which said buck and shoe are in register and in spaced relation, means for initially moving said shoe toward said buck in opposition to said biasing force, a member moved with said shoe during the initial movement of said shoe, means including a cam between said member and said shoe for moving said shoe relative to said carriage into final pressing engagement with said buck, and means for locking said member to said carriage in the position to which it is moved during the initial movement of said shoe.

70 8. An ironing press comprising a buck, a carriage, a shoe carried by said carriage and movable relative to said carriage, means for biasing said shoe toward said carriage, means for relatively moving said buck and shoe to a position in which said buck and shoe are in register and in spaced relation, means for initially moving said shoe toward said buck in opposition to said biasing force, a member moved with said shoe

during the initial movement of said shoe, means including a cam between said member and said shoe for moving said shoe relative to said carriage into final pressing engagement with said buck, and means actuated upon initial movement of said cam in the direction to move said shoe toward said buck for locking said member to said carriage.

9. An ironing press comprising a buck, a carriage, a shoe carried by said carriage and movable relative to said carriage, means for relatively biasing said shoe toward said carriage, means for moving said buck and shoe to a position in which said buck and shoe are in register and in spaced relation, means for initially moving said shoe toward said buck in opposition to said biasing force, a member moved with said shoe during the initial movement of said shoe, means including a cam between said member and said shoe for moving said shoe relative to said carriage into final pressing engagement with said buck, means actuated upon initial movement of said cam in the direction to move said shoe toward said buck for locking said member to said carriage, and means actuated upon movement of said cam in the direction to release the pressure between said buck and said shoe for releasing said member from said carriage.

10. An ironing press comprising a buck, a carriage, a shoe carried by said carriage and movable relative to said carriage, means for relatively moving said buck and shoe to a position in which said buck and shoe are in register and in spaced relation, means for initially moving said shoe toward said buck, a member moved with said shoe during the initial movement of said shoe, means including a cam between said member and said shoe for moving said shoe relative to said carriage into final pressing engagement with said buck, and a pawl carried by said member and moved into engagement with notches in said carriage upon initial movement of said cam in the direction to move said shoe toward said buck for locking said member to said carriage.

11. An ironing press comprising a buck, a carriage, a shoe carried by said carriage and movable relative to said carriage, means for relatively moving said buck and shoe to a position in which said buck and shoe are in register and in spaced relation, means for initially moving said shoe toward said buck, a member moved with said shoe during the initial movement of said shoe, means including a cam between said member and said shoe for moving said shoe relative to said carriage into final pressing engagement with said buck, and a pawl carried by said member and moved into engagement with notches in said carriage upon initial movement of said cam in the direction to move said shoe toward said buck for locking said member to said carriage, said pawl being moved out of engagement with said notches upon final movement of said cam in the direction to release the pressure between said buck and said shoe.

12. An ironing press comprising a buck, a carriage, a shoe carried by the carriage and movable relative thereto, a member movable relative to the carriage for initially moving the shoe relative to said carriage toward the buck, means for locking said member to said carriage at the end of the initial movement, and pressure developing mechanism between said member and said shoe for moving said shoe into pressing engagement with said buck.

13. An ironing press comprising a buck, a carriage, a shoe carried by the carriage and movable relative thereto, means for initially moving said shoe relative to said carriage into contact with said buck, a member movable relative to said carriage to a position corresponding to the position of the shoe at the end of the initial movement, means for locking the member to the carriage in this position, and pressure developing mechanism between said member and said shoe for moving said shoe into pressing engagement with the buck. 10
14. An ironing press comprising a buck, a carriage, a shoe carried by the carriage and movable relative thereto, means for initially moving the shoe relative to the carriage into contact with the buck, a member movable relative to the carriage to a position corresponding to the position of the shoe at the end of the initial movement, means including a cam journaled in said member for 15 moving said shoe into pressing engagement with said buck, and means operated upon the initial movement of said cam in the direction to move said shoe into pressing engagement with the buck for locking said member to said carriage. 20
15. An ironing press comprising a buck, a carriage, a shoe carried by the carriage and movable relative thereto, means for initially moving the shoe into contact with the buck, a member movable relative to the carriage and having a recess 25 therein, said member being movable to a position corresponding to the position of the shoe at the end of the initial movement, means including a shaft journaled in said member and having a cam in said recess for moving said shoe into pressing engagement with said buck, and a U-shaped pawl carried in said recess and extending on each side of said shaft, said pawl being moved into engagement with notches in said carriage for locking 30 said member to said carriage upon initial move- 35
- ment of said cam in the direction to move said shoe into pressing engagement with said buck. 16. In an ironing press, a support, a hollow buck having a perforated upper surface and an enclosed lower wall, an opening in said lower wall for draining moisture condensed in said buck, and means including a hollow member of rubber arranged between said buck and said support below said opening for resiliently supporting said buck and for draining the condensed moisture. 10
17. In an ironing press, a support, a hollow buck having a perforated upper surface and an enclosed lower wall, an opening in said lower wall for draining moisture condensed in said buck, and means including a hollow rectangular member of rubber arranged between said buck and said support below said opening for resiliently supporting said buck and for draining the condensed moisture. 15
18. In an ironing press, a support, a hollow buck carried by said support, said buck having a perforated upper surface and an enclosed lower wall, a drain for draining moisture condensed in said buck, and an enclosed pan carried by said support having an opening beneath said drain, said opening being located so that condensed moisture in the pan is not spilled when the press is tipped. 20
19. In an ironing press, a support, a hollow buck carried by said support, said buck having a perforated upper surface and an enclosed lower wall, a drain for draining moisture condensed in said buck, an enclosed pan carried by said support having an opening beneath said drain, said opening being located so that condensed moisture in the pan is not spilled when the press is tipped, and means including a spring clip for removably supporting said pan on said support. 30

JOHN S. VISSCHER.
